UNITED STATES PATENT OFFICE.

THOMAS F. COONEY, OF NEW HAVEN, CONNECTICUT.

HAIR-CURLING DEVICE.

Application filed January 26, 1925. Serial No. 4,734.

To all whom it may concern:

Be it known that I, THOMAS F. COONEY, citizen of the United States, residing at New Haven, in the county of New Haven 5 and State of Connecticut, have invented certain new and useful Improvements in Hair-Curling Devices; and I do hereby declare the following to be a full, clear, and exact description of the invention, such as will enable others skilled in the art to which it appertains to make and use the same.

This invention relates to an improvement in hair curling devices, and has as its special object to provide means whereby an equal 15 amount of hair is enclosed within the crimping member, thus insuring a uniform wave and avoiding shearing or otherwise damaging the hair. The novelty of construction and advantage of the device will be 20 fully understood from the following description and claims when taken in connection with the annexed drawings, in which—

Figure 1 represents a plan view of the improved curling device in a closed position—

Figure 2 is a side elevation of the device 25 partially opened—

Figure 3 is a plan view of the device fully opened—

Figure 4 is a side elevation of the device 30 fully opened and engaged with a strand of hair, and

Figure 5 is an enlarged broken view of the loop end of the supporting frame.

A skeleton construction of flat wire comprising the parallel side bars 1, 2, merging into the loop 3 at one end, and terminating in the apertured ears 4, 5, at the opposite end, constitutes the frame portion adapted 35 to support the crimper comprising a single metal strip having the central loop 6 and the diverging arms 7 and 8.

These arms are closed near the loop 6 and are located, at such closed point, between the ears 4, 5, of the frame, and are pivotally 40 supported on the connecting pin or rivet 9.

When the device is in open position, as shown in Figure 3, the divergent arms 7, 8, are inserted into the hair 13 to gather a certain amount therebetween, as shown in 45 Figure 4. The device is then carried down to bring the arms near the end of the gathered strand of hair in readiness for curling the same. By means of the frame, the device is then rotated until the strand 50 of hair is closely wound about the bars. The ends of the bars are then brought to

gether and inserted between the neck 10 of the frame and are held in such position against accidental displacement by the projections 11 engaging the elongated opening 60 12 near the ends of the bars.

When the device is closed, either empty or engaged with the hair, the loop 3 of the crimper and 6 of the frame lie opposite each other in the same plane, and will thus furnish means for applying the necessary leverage to release the closed bars from their locked position, as shown in Figure 2. The loop 3 of the frame is firmly held by one hand, while with the other hand, sufficient 65 70 downward pressure is applied to the loop 6 to effect such release.

Making the crimping member of the device of a single metal strip, will always insure its arms being rigidly held in opposite 75 relation to each other, and thus avoid shearing or otherwise injuring the hair, which would be very liable to occur if individual arms were employed, each having an independent vertical movement on its pivotal 80 support. With such a construction, it would be difficult to insert the arms into the hair without displacing their opposed relation, which would not only prevent their gathering an equal amount of hair at each 85 insertion, but the pressure of the winding curls about the arms would tend to bring them again opposed to each other and produce a shearing effect on the hair, besides, one of the arms would be liable to remain 90 in its closed position, while the other is released, thus making it difficult to extract the arms without unrolling the hair.

With the single element crimper, its arms are always opposed to each other, and when 95 laterally separated a predetermined distance, an equal amount of hair is gathered at each insertion of its arms, which are as readily inserted and withdrawn as an ordinary hair pin, and without injury to the 100 hair or displacement of the curls.

Having thus described my invention what I claim is:—

1. In a hair curling device of the character described, comprising a hair crimping member made of a single metal strip folded upon itself to form opposed arms and a loop formed at the center of the strip, and a support pivoted to the crimping member in 105 advance of the loop.

2. In a hair curling device of the character described, comprising a hair crimping 110

member constructed of a single metal strip folded at the center to form a loop with opposed arms projecting therefrom, a skeleton frame having a loop at one end and 5 open at its opposite end, said crimping member pivotally supported at such open end at a point in advance of its central loop,

and adapted to be enclosed within the frame to bring said central loop outside of the frame and in the same plane with the loop 10 of the frame.

In testimony whereof I affix my signature.

THOMAS F. COONEY.
